UNITED STATES PATENT OFFICE.

JOHN TALIAFERRO THOMPSON, OF NEWPORT, KENTUCKY.

GUN-BARREL.

1,329,444.

Specification of Letters Patent.

Patented Feb. 3, 1920.

Application filed June 30, 1919. Serial No. 307,739.

To all whom it may concern:

Be it known that I, JOHN TALIAFERRO THOMPSON, citizen of the United States of America, and resident of Newport, in the 5 county of Campbell and State of Kentucky, have invented new and useful Improvements in Gun-Barrels, of which the following is a specification.

This invention relates to guns and more 10 particularly to an improved rifled barrel for a gun.

In firearms provided with rifling it has been customary to rifle the barrels throughout their entire length and to employ projectiles which are somewhat larger than the bore of the barrels so that the projectiles will be caused to sink into the rifling and will be subjected to the rotative effect of the rifling throughout substantially the entire 20 length of the barrels. This construction has a number of disadvantages, chief of which are the following: Owing to the fact that the projectile is somewhat larger than the bore of the barrel there is an excessive 25 amount of friction between the projectile and the barrel. This results in a loss of velocity of the projectile, rapid heating of the barrel, undue wear on the barrel, etc., etc. The wear on the barrel is so great in 30 fact that the rifling soon becomes ineffective and the life of a gun is thereby rendered exceedingly short, especially in comparatively high-power guns. The heating of the barrel is very troublesome owing to the fact 35 that it endangers the hands of the user and necessitates his continually guarding against contact therewith, this trouble being particularly pronounced in rapid fire guns such as automatic and semi-automatic guns.

40 Moreover, in automatic and semi-automatic guns where the breech action is controlled by the breech pressure and where it is essential to the uniform and reliable operation of the guns that the breech pressure 45 developed at each firing be substantially the same, the aforesaid construction is particularly unsatisfactory for the following reasons: With the projectile larger than the bore so that the rifling will bite thereinto, 50 the resistance offered to the successive projectiles in passage through the bore is widely variable, due principally to variations in the size of the projectiles, to the rapid heating and consequent expansion of 55 the barrel, to the rapid fouling of the bore. The wide variation in the resistance to the

successive projectiles produces a corresponding variation in the breech pressure reacting on the breech action, resulting in a nonuniform action of the breech closure and 60 in some cases in a complete failure of the breech mechanism to function. For example, if the breech action is adjusted to operate properly with a certain breech pressure, the breech may open too quickly or too 65 forcibly if the reacting pressure increases due to the aforesaid variable factors, or the breech may open too slowly or not sufficiently if the reacting pressure decreases.

The object of the present invention is to 70 overcome the aforesaid and other objections to guns of the character referred to. More particularly the object of the invention is to increase the velocity of projectiles in rifled guns, at the same time giving the projectiles 75 sufficient rifling effect to afford accurate firing, to decrease the heating and wear of the barrel, to decrease fouling of the barrel, and in the case of automatic guns to render the operation of the breech action 80 uniform and reliable.

In one aspect the invention comprises a gun barrel having a bore which is smooth throughout a portion of its length and which is rifled throughout a portion of its 85 length, the grooves of the rifling having a diameter greater than the diameter of the smooth bore throughout at least a part of said rifled portion and the lands between the grooves of the rifling having a diameter 90 less than the diameter of said smooth portion throughout at least a part of said rifled portion.

In another aspect the invention comprises a gun barrel whose bore is gradually constricted throughout a portion of its length and is provided with rifling throughout the constricted portion, the constricted portion preferably being confined to a short length of the barrel at the muzzle end and the 100 rifling preferably being confined to the constricted portion. The bore of the barrel, other than the said portion, is preferably substantially equal in diameter to the diameter of the projectiles so that the projectiles 105 will pass freely therethrough until they reach the constricted portion when they will be subjected to the rifling effect just before leaving the barrel. The rifling grooves preferably begin at substantially zero depth at 110 the beginning of the constricted portion and gradually increase in depth through-

out the constricted portion. Owing to the gradual constriction of said portion no shoulder or sudden change in resistance is afforded to the projectiles and owing to the gradual deepening of the rifling grooves the projectiles are set into rotation more gradually. The gradual increase in the depth of the rifling grooves is so proportioned to the gradual constriction of the bore that the cross-sectional area of the bore is maintained substantially constant throughout said constricted portion of the bore and substantially equal to the diameter of the cylindrical portion of the bore, whereby when the projectiles pass through the constricted portion they may gradually extrude into the rifling grooves and not be materially retarded by the constriction.

I am aware that it has been proposed to repair firearms in which the rifling has been worn away by renewing the rifling only throughout a portion of the bore, and the present invention is not to be confused with any such expedient.

In order more clearly to set forth my invention I have illustrated one concrete embodiment thereof in the accompanying drawings, in which:—

Figure 1 is a longitudinal section through my improved gun-barrel;

Fig. 2 is an enlarged section of the barrel at the muzzle end showing the constricted portion of the bore prior to the cutting of the rifling grooves; and

Fig. 3 is an enlarged section of the barrel at the muzzle end showing the constricted portion of the bore after the rifling grooves have been cut.

Referring to the drawings, a gun-barrel is shown at 1 provided at the breech end with a firing chamber 2 and an exteriorly threaded portion 3 by which the barrel may be attached to a receiver (not shown). The bore 4 of the barrel is finished smooth from the chamber 2 to a point preferably from three to twelve inches from the muzzle end of the barrel and with a diameter substantially equal to that of the bullet which in a service rifle is .308 inches.

At the muzzle end the bore is tapered or constricted gradually as at 5 until at the muzzle the diameter of the bore is reduced as for example to .300 inches. In this constricted region of the bore rifling grooves 6 are formed, the grooves beginning at the beginning of the constricted portion and extending to the muzzle of the barrel. The grooves begin at substantially zero depth and gradually increase in depth. The number of grooves and the pitch of their spiral may be determined in accordance with usual practice. Preferably the grooves are tapered in depth reverse to the taper of the constricted portion 5 of the barrel so that at the muzzle the diameter of the bore at the

bottoms of oppositely disposed grooves is slightly greater than the diameter of the smooth portion of the bore, the increase in depth depending upon the constriction, the number and width of the grooves, etc. By gradually deepening the rifling grooves the cross-sectional area of the constricted portion of the bore, including the cross-sectional area of the grooves, is maintained substantially constant throughout the length of the 75 constricted portion and substantially equal to the cross-sectional area of the smooth portion of the bore. Therefore when a bullet enters the constricted portion 5 of the bore the metal which is gradually extruded from the 80 bullet due to the pressure exerted upon it by the tapered wall of the bore finds an increasing amount of space through the constricted portion. No axial deformation of the bullet is caused by the constriction of the bore but 85 merely a radial displacement, and to a slight extent a circumferential displacement, of the cylindrical surface of the bullet. With this construction the bullet secures a good grip on the rifling and the necessary rotation of the bullet is assured.

In Fig. 2 I have shown, on an enlarged scale, the muzzle end of a gun provided with a bore constricted as at 5. For clearness of illustration the bore is shown in the condition which it assumes prior to the formation of the rifling grooves, the depth to which the grooves are to be cut being indicated by dot and dash lines. It is to be especially noted that the mergence of the constricted portion of the bore into the smooth portion 4 of the bore is very gradual and therefore no sudden retardation of the bullet which might tend to explode the barrel is occasioned.

From the preceding description it will appear that the diameter of the grooves of the rifling (the diameter of the dot and dash lines in Fig. 2) is greater than the diameter of the smooth bore and that the diameter of the lands between the rifling grooves (the diameter of the constricted portion of the bore) is less than the diameter of the smooth bore, which if extended throughout the entire length of the barrel would have a 115 diameter of the dotted lines in Fig. 2. While I have shown the rifling grooves increasing in diameter toward the muzzle this diameter may be constant or even decreasing toward the muzzle depending upon the type of projectile and type of gun used.

From the foregoing description it is apparent that I have provided an improved gun which, because of its smooth bore and small extent of rifling, permits the bullets 125 to be discharged at a greater velocity with the same amount of powder charge; which, because of the smooth bore, has less friction between the bullets and the bore and, as a consequence, less heating of the barrel, less 130

leading and less wear; and which, due to the higher velocity of the bullets, causes a greater penetration. Where my improved barrel is employed on automatic or semi-automatic guns, the features herein set forth are particularly advantageous, as a more uniform breech pressure upon which guns of this type depend for their functioning, results from a more uniform reaction from the bullet.

10 I claim:

1. A gun barrel having a bore whose rearward portion is smooth and whose forward portion is rifled, the grooves of the rifling beginning at zero depth and gradually flaring outwardly and the lands of the rifling beginning at zero height and gradually tapering inwardly.
2. A gun barrel having rifling grooves throughout a portion of its length, the rifling grooves beginning at substantially zero depth and gradually increasing in depth toward the muzzle of the barrel so

that the diameter between the bottoms of opposed rifling grooves is greater than the 25 diameter of the bore.

3. A gun barrel having a bore which is smooth throughout a portion of its length and which is rifled throughout a portion of its length, the grooves of the rifling having 30 a diameter greater than the diameter of said smooth portion of the bore throughout at least a part of said rifled portion.

4. A gun barrel having its bore gradually constricted throughout a portion of its 35 length and having rifling grooves in the constricted portion, the rifling grooves beginning at substantially zero depth at the beginning of said portion and gradually flaring outwardly so that the diameter between 40 the bottoms of opposed rifling grooves gradually increases thereby to compensate for the constriction.

Signed by me at Boston, Massachusetts, this twenty-sixth day of June, 1919.

JOHN TALIAFERRO THOMPSON.
